UNITED STATES PATENT OFFICE.

HANNAH JACOBS, OF BROOKLYN, NEW YORK.

HAIR-WAVING DEVICE.

Application filed April 6, 1927. Serial No. 181,397.

My invention relates to devices for waving hair, and it belongs to the class of device shown in my U. S. Patent No. 1,477,873.

The object of the present invention is to provide a simple device for winding a lock of hair in the form of a helix upon a rod or curling pin to prepare the hair for producing what is commonly called a permanent wave. The present device comprises a rod or curling pin on which a lock of hair is adapted to be wound, and this is preferably attached to a plate or base which lies close to the head and protects the head from the heat produced by the heater. In addition to the pin on which the hair is wound there is a member slidable along the pin and revolvable in relation thereto, and this member presses upon the coil of hair and at the same time carries it around the pin in order to lay it in the form of a helix thereon; and afterwards this member serves to hold the free end of the hair upon the pin while the heat is being applied to bake the hair. This revolving and sliding member is adapted to automatically affect the winding of the hair in a single layer upon the pin with each turn of hair laid closely to or slightly overlapping the adjacent turn. The lock of hair itself serves to advance this sliding and revolving member along the pin without particular attention on the part of the operator. The device is simple and rapid in its operation and therefore where a number of pins are to be applied to a head of hair the work of preparing or winding the hair may be carried out expeditiously. Furthermore, the lock of hair is laid smoothly and tightly upon the curler and in regular turns so that less skill is required on the part of the operator for this operation. In fact, no particular skill is required to execute this part of the waving operation when the present device is used. Other objects and advantages will be set forth in the following detailed description of my invention.

In the drawings forming part of this application,

Figure 1 is a side elevation of a device embodying my invention in one form showing the condition of the parts just after the winding operation has been started,

Figure 2 is a similar view showing the parts when the winding operation is about completed,

Figure 3 is an elevation of the revolving

and sliding member which lays the hair upon the rod,

Figure 4 is a longitudinal sectional view thereof taken on the line 4—4 of Figure 3,

Figure 5 is a cross sectional view taken on the line 5—5 of Figure 3,

Figure 6 is an end elevation of the same member as is shown in Figure 3,

Figure 7 is an elevation of the device shown in Figures 1 and 2 with the sliding member moved inwardly on the pin at the completion of the winding operation,

Figure 8 is a sectional view taken on the line 8—8 of Figure 7,

Figure 9 is an elevation of a modified form of my device,

Figure 10 is an enlarged elevation of the sliding member of the same device,

Figure 11 is a sectional view taken on the line 11—11 of Figure 9, and

Figure 12 is a sectional view taken on the line 12—12 of Figure 10.

I will first describe the form of my invention which is shown in Figures 1 to 8 inclusive. The essential portions of the device as far as the present invention is concerned are the rod or pin on which the hair is wound, and the sliding and revolving member co-operating with the pin. In the drawings I have shown the member for receiving the hair as comprising a pin 1 although it will be understood that this member may take various forms as long as it is adapted to have a lock of hair wound thereon. This member is shown attached at one end to a base or plate 2 which acts as a shield to prevent the heat from the heater (not shown) from passing to the head. While I have shown the clip 3 for engaging the enclosing tube, the same does not form any part of the present invention. The pin 1 extends outwardly at right angles to the base or shield and it is adapted to be held at right angles to the portion of the head near the lock of hair which is to be wound upon the device. In this form of the device the sliding and revolving member is shown as consisting of a sleeve 4 which has a central bore 5 to permit the sleeve to slide freely on the pin 1 and also to revolve thereon. The sleeve is shown as provided at its outer end with a knurled flange 6 adapted to be gripped by the fingers in the operation of revolving the sleeve. The hair engaging

portion of the sliding member comprises a 110

circular portion 7 which is clamped upon the outer surface of the sleeve 4 by a clamping ring 8 which is forced thereon and permanently fixes the member 7 to the sleeve. 5 This member 7 is shown as of cylindrical formation and it has projecting from one end a finger or prong 9 which is resilient and is preferably arched or curved in the shape shown in Figure 3, and its outer or 10 free end projects inwardly toward the axis of the revolving member. There is a second finger or arm 10 angularly disposed in relation to the finger 9 and it also extends from the same end of the member 7 and it is preferably somewhat longer than the finger 9 15 as is shown in Figures 1 to 4. In addition, I have shown a member 11 extending from the member 7 in the same general direction as the fingers 9, 10 and angularly disposed 20 in relation to both of them. This member is bent back upon itself at the point 12 and is continued in the form of a rearwardly extending member 13 which extends over the sleeve 4 where it may be pressed downwardly by the finger which grasps the sleeve, in 25 order to reduce the spacing between the two portions 11, 13.

The method of using this form of device is as follows: First, a lock of hair is combed 30 out from the head and the guard 2 is clamped upon this lock of hair 14 close to the head; and the curling pin 1 is held so that it extends outwardly from the head as shown in Figures 1 and 2. The lock of hair is given 35 one or more turns around the rod, as shown at 15 in Figure 1 and the revolving member is pushed along the pin 1 until the fingers 9, 10, 11 extend over the first turn or two of hair on the pin. The free end of the 40 lock of hair is then passed between the finger 11 and the member 13 passing over the former and under the member 13 as shown in Figure 1. The revolvable member may now be pushed slightly toward the guard 2 45 along the pin 1 until the lock of hair which fastens under the member 13 lies close to the end of the sleeve 7. The revolvable member is now turned upon the pin, either clockwise or counterclockwise, according to 50 which direction the lock of hair is first started on the pin. In the condition shown in Figure 1 the revolvable member will be turned counterclockwise and this will cause the lock of hair to be laid tightly upon the 55 surface of the pin in the form of a helix, each coil or turn lying adjacent the last one. As the sleeve 4 is revolved the lock of hair will cause it to advance along the pin to the right in Figure 1 in order that each coil 60 of hair may lie adjacent the next preceding coil until the lock of hair has been fully wound upon the pin as shown in Figure 2. The action of the lock of hair in advancing the revolvable member on the pin eliminates 65 the necessity of the operator controlling the

feeding of the revolving member, so that the feeding action takes place automatically as this member is revolved. The fingers 9, 10, as well as the member 11 all press upon the lock of hair as it is being wound, and cause 70 it to fit snugly against the pin. After the entire lock of hair has been wound on the pin as shown in Figure 2, the revolving member may then be moved inwardly or towards the shield to the position shown in Figure 75 7 in order that the fingers 9, 10, 11 may project over and engage the end of the coils of hair. Any type of heater may now be placed over the device to enclose the hair and to apply the necessary heat for fixing the 80 wave or rendering it permanent, and it will be understood that suitable chemicals may be applied to the hair to carry out this operation.

While the lock of hair is being wound on the pin pressure may be applied by the finger of the operator upon the member 13 to increase the friction or pressure of the members 11 and 13 on the hair passing between them and this will create tension to cause the hair to be applied more tightly upon the pin.

The device shown in Figures 9 to 11 inclusive is of modified construction. This form of device includes the pin, the same as 95 in the former device, and it includes the sleeve 4 with the knurled flange 6 for manipulating it. In this case I have shown three resilient fingers 17, 18, 19 projecting 100 forwardly from the member 7 and these all press inwardly toward the axis of the sleeve. The fingers 17 and 19 are shown arranged close together or slightly overlapping, as shown in Figure 12, before they are expanded; whereas, the spacing of the finger 18 105 from the adjacent edges of the fingers 17, 19 is somewhat greater in order to provide a lateral space 20 through which the lock of hair may extend. In using this form of device a lock of hair is combed out from the 110 head and one or two turns are made around the pin 1. The revolving or winding member is then moved along the pin until the fingers 17, 18, 19 all engage the turns of hair on the 115 pin with the free or unwound portion of the lock of hair passing out through the space 20 between the fingers as is shown in Figure 9. The revolving member is then moved further inwardly until the free portion of the 120 lock of hair lies adjacent the edge of the member 7. The revolving member is then turned counterclockwise, in the example shown in Figure 9, around the pin 1, causing the lock of hair to be laid in the form of a coil upon the pin, and in this case, also, the lock of hair will serve to advance the revolving member along the pin or to the right in Figure 9. When the hair has been entirely wound upon the pin the revolving member is left in place on the pin to hold 130

the hair while the baking operation is taking place.

From the above it will be apparent that I have provided a very simple device for tightly winding a lock of hair on a curling pin for use in permanent waving. The device is adapted to wind the hair in regular, even turns each turn lying closely adjacent the preceding turn with sufficient tension to accomplish the desired purpose.

Having described my invention, what I claim is:

1. In a device of the character described the combination of a curling pin around which a lock of hair is adapted to be wound, and a member slidably and revolvably engaging said pin and having resilient fingers for pressing the hair against said pin when said revolvable member is revolved on the pin with the free end of the lock of hair extending outwardly between said fingers.

2. In a device of the character described the combination of a curling pin around which a lock of hair is adapted to be wound, and a member slidably and revolvably engaging said pin and having a plurality of resilient fingers arranged around the pin and adapted to press the lock of hair upon the pin, as said revolvable member is revolved on the pin with the lock of hair extending outwardly between said fingers.

3. In a device of the character described the combination of a curling pin around which a lock of hair is adapted to be wound and a member slidably and revolvably engaging said pin and having a plurality of fingers of different lengths projecting from said revolvable member so as to press upon the coils of hair and against said pin as the revolvable member is revolved on said pin.

4. In a device of the character described the combination of a curling pin around which a lock of hair is adapted to be wound and a member slidably and revolvably engaging said pin and having a knurled projection, said revolvable member having a plurality of resilient fingers extending therefrom and adapted to press the lock of hair against said pin.

5. In a device of the character described the combination of a curling pin around which a lock of hair is adapted to be wound and a member slidably and revolvably engaging said pin, said member having arched fingers projecting therefrom, the free ends of which are adapted to press the coil of hair as it is wound on said pin, said fingers having a lateral opening between them through which the free end of the lock of hair is adapted to feed onto the pin as said revolvable member is revolved on the pin.

6. In a device of the character described the combination of a curling pin around which a lock of hair is adapted to be wound, and a member slidably and revolvably engaging said pin and including a sleeve, fingers projecting therefrom, adapted to press the coil of hair upon the pin as said sleeve is revolved, the free end of the lock of hair being adapted to pass over one of said fingers and between said latter finger and an adjacent finger onto said pin, and a resilient member extending backwardly over one of said fingers to apply adjustable tension to the lock of hair while said sleeve is being revolved on said pin.

Signed at the city, county and State of New York, the 24th day of February, 1927.

HANNAH JACOBS.
